(57) CLAIM

The ornamental design for a bed sheet as shown and described.

DESCRIPTION

FIG. 1 is a front view of a bed sheet showing my new design; FIG. 2 is a rear view of the bed sheet; FIG. 3 is a right side view of the bed sheet; FIG. 4 is a left side view of the bed sheet; FIG. 5 is a top view of the bed sheet; FIG. 6 is a bottom view of the bed sheet; and, FIG. 7 is a top front side perspective view of the bed sheet. The broken lines along an edge of the article in FIGS. 1, 2, 5, and 7 are illustrative of stitching forming no part of the claimed design. The U-shaped broken lines adjacent to the opening in FIG. 6 are illustrative of stitching forming no part of the claimed design. The other broken lines in FIG. 6 are illustrative of a boundary inside which forms no part of the claimed design.
